UNITED STATES PATENT OFFICE.

JOHN ROBERTS AND JAMES E. BLISS, OF FAUST, NEW YORK.

TIE.

No. 865,945.

Specification of Letters Patent.

Patented Sept. 10, 1907.

Application filed January 19, 1907. Serial No. 353,185.

To all whom it may concern:

Be it known that we, JOHN ROBERTS and JAMES E. BLISS, citizens of the United States, residing at Faust, in the county of Franklin and State of New York, have 5 invented new and useful Improvements in Ties, of which the following is a specification.

The invention relates to an improvement in ties, and particularly to a metallic tie constructed to provide a firm support for railroad rails.

10 The main object of the present invention is the production of a metallic tie constructed to afford a firm support for railroad rails, and to provide a means for securing the rail in position on the tie, the tie structure including a rail cushioning means arranged to absorb the 15 vibrations of the rail incident to the travel thereon and prevent transmission of such vibration to the tie.

The invention will be described in the following specification, reference being had particularly to the accompanying drawings, in which:

20 Figure 1 is a plan view illustrating the use of our improved tie, Fig. 2 is a longitudinal section through the tie on line 2—2 of Fig. 1, illustrating the preferred form of cushioning means, Fig. 3 is a similar view illustrating a modified form of cushioning means, Fig. 4 is a plan view 25 of the tie removed. Fig. 5 is a transverse section on line 5—5 of Fig. 2.

Referring particularly to the drawings, our improved tie comprises a rectangular body 1 formed in the relatively upper surface with a centrally disposed depression 2. Beyond the depression the tie is approximately 30 solid to provide heads 3 to receive the rails, the end walls of the depression being arranged within the rail receiving portion of the tie. The depression 2 is of somewhat less extent transversely and vertically than 35 the similar dimensions of the tie, whereby the tie is in effect of hollow construction between the heads.

Each head 3 is formed on the relatively upper surface with a rail receiving recess 4, one-half of the recess being formed by undercutting the material of the head, where- 40 by to provide a lip 5 overlying a portion of the recess and spaced from the bottom wall thereof. Between the relatively inner-ends of the lips 5 of the tie, the thickness of the body 1 is reduced by a distance approxi- 45 mately equal to the thickness of the lip, so that the inner half of the recess 4 is fully open, the inner boundary thereof being defined by a comparatively slight shoulder 6. Centrally of the length of the recess 4 the heads 3 are each formed with a vertically extending opening 7 adapted to contain the vibration absorber, as will 50 presently appear.

The inner surface of the lip 5 is shaped to conform to the curvature of a rail base 8, and the depth of the recess 4, that is the distance from the inner surface of the lip

5 to the bottom wall of the recess is slightly in excess of the thickness of the rail flange 8.

55

A tie plate 9 is arranged to cover the surface of the tie between the recesses 4, the respective ends of said plate overlying the open portion of the recess and shaped, as at 10, to conform to the contour of the base flange of the rail. The tie plate is co-extensive in width with the width of the tie, thereby covering the depression 2 therein. The tie plate is secured in place by means of bolts 11, shaped at their lower ends to provide hooks 12, adapted to engage appropriately formed openings 13 in the side walls of the depression 2, the upper ends of the bolts being threaded and passed through registering openings 14 in the tie plate 9, said bolts being secured beyond the tie plate by nuts 15 to co-operate with the threaded ends thereof.

60

The openings 7 in the recesses 4 are adapted to contain a means for absorbing to a considerable degree the vibration of the rails, whereby to avoid transmission of this vibration to the tie with the consequent injurious effect upon the road bed. As shown in Fig. 2 the preferred form of shock absorber is in the form of a cylindrical body of resilient material, as rubber 16, snugly fitting in the openings 7 in the tie with the upper end of the body projecting above the bottom wall of the recess 4. In Fig. 3 the shock absorber is shown in the form of a coil spring 17, seated in the openings 7 and normally 80 projecting above the bottom of the recesses 4.

70

The rails are secured in position on the tie in the manner illustrated in Fig. 2, the outer projection of the base flange of the rail being inserted beneath the lip 5, the inner portion of said flange being secured beneath the 85 appropriately formed end of the tie plate 9. The latter is secured in position by the use of the bolts 11, thereby securing the rails to the tie in a manner to provide a firm support therefor without interfering with the independent movement of the rail essential to its expansion 90 and contraction under changes of the temperature.

85

The rail rests directly upon the shock absorbing body, hence materially reducing the transmission of the vibration of the rail to the tie, and thereby avoiding to a considerable extent a vibration of the tie with consequent damaging influence upon the roadbed. The under surface of the tie is formed with a concavity 18 of greater longitudinal extent than that of the depression 2, forming in effect a recess for the reception of material forming the roadbed, which in place will tend to prevent independent longitudinal movement of the tie.

90

In the use of the tie as a support for the meeting ends of railroad rails, we prefer to combine with the tie reinforcing plates 19 designed to be applied to opposite sides of the web portions of the respective rails and be secured to the rail and to each other by bolts 20. The 100 105

plates 19 are adapted to rest squarely upon the lips 5 and the flange engaging portion of the tie plate 9, thereby materially reinforcing the rail securing means of the tie, while at the same time securing the meeting ends of 5 the rails in a manner to insure their alinement under usual conditions of travel.

The tie constructed as described provides a simple and convenient support for railroad rails, in which the vibration of the rails will be absorbed to a material extent. The rails may be released at any time by removing the tie plate 9, as will be obvious.

While preferring the use of duplicate reinforcing plates 19, it is obvious that only one such plate may be used if desired. Furthermore, the tie plate 9 may be formed in one or more sections with independent securing means. The depression 2 may be used to contain a tie ballast, if desired.

Having thus described the invention what is claimed as now, is:—

A tie formed with a central depression, and beyond said depression with transversely extending rail receiving recesses, a portion of the tie overlying a part of each recess, a tie plate extending from one recess to the other and terminally formed to overlie a portion of each recess, and bolts having removable engagement with the walls of the depression and adapted to secure the tie plate in place, in combination with tie reinforcing plates to be secured to the rail and rest upon the recess overlying portions of the tie plate.

In testimony whereof, we affix our signatures in presence 30 of two witnesses.

JOHN ROBERTS.
JAMES E. BLISS.
